US0D1091316S

(12) **United States Design Patent** (10) **Patent No.:** **US D1,091,316 S**
(45) **Date of Patent:** **** Sep. 2, 2025**

(54) **BOTTLE**

(71) Applicant: **H.J. Heinz Company Brands LLC**,
Pittsburgh, PA (US)

(72) Inventors: **Michelle Marie Hayden**, San
Francisco, CA (US); **Peter Brian
Clarke**, Newton, CT (US); **James E.
McCay**, Fairfield, CT (US); **Sean
Evelich**, Hamden, CT (US); **Trond
Erik Tollefsen**, London (GB)

(73) Assignee: **H.J. Heinz Company Brands LLC**,
Pittsburgh, PA (US)

(**) Term: **15 Years**

(21) Appl. No.: **29/957,797**

(22) Filed: **Aug. 15, 2024**

Assistant Examiner — Amanda Kay Birdwell

(74) *Attorney, Agent, or Firm* — Fitch, Even, Tabin & Flannery LLP

CLAIM

The ornamental design for a bottle, as shown and described.

DESCRIPTION

FIG. 1 is a top, front perspective view of a bottle in accordance with our new design;

FIG. 2 is a bottom, rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown illustrate portions of the bottle. The dash-dot lines represent the bounds of the claim. The broken lines form no part of the claim.

1 Claim, 7 Drawing Sheets
